UNITED STATES PATENT OFFICE.

PETER STORZUK, OF ETHELBERT, MANITOBA, CANADA.

THRESHING AND SEPARATING MACHINE.

1,175,088.

Specification of Letters Patent. Patented Mar. 14, 1916.

Application filed June 24, 1914. Serial No. 847,032.

To all whom it may concern:

Be it known that I, PETER STORZUK, citizen of the Dominion of Canada, residing at the village of Ethelbert, in the Province of 5 Manitoba, Canada, have invented certain new and useful Improvements in Threshing and Separating Machines, of which the following is a specification.

My invention relates to improvements in 10 grain threshers and separators, and has for its object primarily, the improvement of the means for separating the grain from the straw after these have passed through the usual cylinders and concave and secondly 15 the means for operating the improved separating decks.

With these objects in view the invention consists in the novel construction and combination of elements hereinafter set forth, 20 and fully illustrated in the accompanying drawing, in which—

Figure 1 is a side elevation of a separating machine, a portion of the siding being broken away to show the separating racks 25 or decks. Fig. 2 is a plan view from above of the separating racks apart from the rest of the machine. Fig. 3 is a sectional end view of the interior of the machine taken upon the line A—B in Fig. 1. Fig. 4 is a 30 view from below of the crank movement by which the separating racks are operated.

Referring to the drawings, in which similar characters of reference refer to similar parts throughout the different views, C indicates the body of the machine having therein 35 suitably placed and housed the cylinder 1 and concave 2, adapted to perform their usual functions and deliver the straw and grain in their threshed condition to the separating racks behind. The separating racks are divided into groups, each of which may consist of as many individual racks as may 40 seem advisable, each group being separate and distinct from the others, and separately 45 supported and operated.

In simple form as shown herein, the racks are divided into two groups D and E the members 3 and 5 of the group D being alternately placed to the members 4 and 6 50 of the group E. The members of the group D are supported at one end by the blocks 7 and 8 carried by the cross bar 9 in turn carried by the rods 10 and 11 pivotally secured to the horizontal frame pieces 12 and 13 and 55 at the opposite end by similar blocks not shown but carried by the cross bar 14 and

the pendulous rod 15 secured to the frame piece 13 and a similar rod on the opposite side of the machine not shown pivoted to the frame piece 12. Similarly the members 60 4 and 6 of the group E are supported at one end by the blocks 16 and 17 carried by the cross bar 18, in turn carried by the rods 19 and 20 pivoted to the horizontal frame pieces 12 and 13, and at the opposite end by 65 blocks not shown but carried by the cross bar 21 and the pendulous rod 22 pivoted to the frame piece 13, and a similar rod on the opposite side of the machine pivotally connected to the frame piece 12. At this point 70 it will be noted that still another cross bar 23 is shown in Figs. 1 and 2 crossing the machine and which bar is connected with the members 4 and 6 of the group E, and supported by rods, one of which 24, is shown in 75 Fig. 1.

F indicates the grain deck or gather board, located below the separating decks and serving to receive the separated grain and carry it to the fanning mill shown as 80 25 in Fig. 1. Below the gather board F and protected thereby from falling grain and dust is the crank mechanism G, a bottom view of which is shown in Fig. 4. This consists of a shaft 26 journaled at 27 and 28 85 to the lower side of the sill pieces 29 and 30 of the frame of the machine. The shaft 26 is provided in its length with the oppositely disposed cranks 31 and 32, and 33 and 34, connected respectively by the rods 35, 36, 37 90 and 38 with the rocking arms 39, 40, 41, and 42 carried by the shafts 43 and 44 journaled to the sills 29 and 30. Rods 45 and 46 connect the rocking arms 41 and 39 respectively with the ends of the cross-bar 18, which 95 project as will be noted in Fig. 1, through the arc shaped openings 47 in the sides of the body 6 of the machine. Similarly, the rocking arms 40 and 42 are connected with 100 ends of the cross bar 23 by rods, only one of which, indicated as 48, is shown, in Fig. 1. The rods 45 and 46 it will be noted by reference to Fig. 3, have their lower ends turned at right angles to form a horizontal portion designated on each respectively as 105 45^x and 46^x, the rod 48 and its corresponding member being provided with similarly turned portions for a similar purpose. The ends of the turned portions of the rods are adapted to reach and be selectively entered 110 in the openings shown at 39^x and 40^x in the swinging members 39 and 40 in Fig. 1, it

being understood that similar openings are provided in the corresponding swinging members not shown in the drawings, to receive the ends of the horizontal portions 5 of the rods pertaining to each. It will be noted that there is a plurality of the openings 39^x and 40^x in the respective members and that disposal of the turned portions of the rods in different openings will operate 10 to diminish or increase the length of the movement of the straw decks as the openings made use of are close to or removed from the pivotal points 43 and 44 of the respective members. Thus the motion of 15 the cranks is transmitted through the rocking arms and rods to the groups D and E of separating racks, imparting to them an alternately reciprocating and rising and falling motion with a tendency to carry in a 20 direction away from the cylinder and concaves 1 and 2 toward the rear end of the machine.

The separating racks themselves it will be noted are of novel construction and designed to have the largest possible separating capacity in proportion to their size. Each of the racks consist of the longitudinally extending spaced apart sides 49 and 50 which are of equal dimension from end to end. Along the upper edges respectively of the sides 49 and 50 are the substantially right angled triangular opensided erections H and H¹ formed by the upwardly and rearwardly sloping pieces 51 and the downwardly sloping pieces 52. The members H and H¹ are much larger than the serration or fish back usually seen in this type of machine, and they are connected each to each by the lateral strips 53, 54, 55 and 56 disposed in spaced relation along the faces of the upwardly sloping pieces 51 and secured thereto. It is preferable that these strips be quite narrow and four in number though the number may be varied should it appear advisable.

It will now be noted that the separating racks as described are practically of skeleton construction, and that the lateral slats 53, 54, 55 and 56, while serving to prevent the straw from dropping through along with the grain separated by agitation, do not impede the dropping of the grain, the area of the openings between the slats, owing to their being positioned upon the up sloping pieces 51, being still greater than would be the open area between the sides H and H¹ if measured upon the plane of their upper edges and without the erections H and H¹ with their connecting lateral slats.

60 The open construction of the triangular members H and H¹ in addition to its value as a means of increasing the separating area on the surface of the racks without unduly

adding to their weight, also adds greatly to their separating function by providing openings in the sides of the members for the passage of flying grain, which, were the sides of the members solid, as is usual in constructions of this character, would be turned back upon the straw and require to be reseparated, thus adding to the work required of the superficial separating area.

In operation the pulley 57 on the crank shaft 26 being set in motion by any suitable means, revolves the crank shaft 26, the crank movement being transmitted as previously mentioned through the rocking arms and rods to the groups D and E, these are caused to reciprocate and agitate the threshed straw and grain received from the cylinder and concave, passing the material toward the tail end of the machine.

Owing to the peculiar skeleton construction of the separating racks, as described, the agitation imparted is very thorough, and grain cannot be carried past the openings in the racks to be blown out with the straw on to the stack and lost, which is the main point sought to be attained in the designing of the machine.

Having thus fully described my said invention what I claim is:—

1. In a threshing machine, a straw deck comprising a plurality of oppositely reciprocated sections, each of said sections having 95 a pair of spaced side walls provided upon their upper edges with upwardly projecting open sided triangular members, and transverse slats connecting the members on one side wall with those on the other.

2. In a threshing machine, a straw deck comprising a plurality of sections alternately placed and connected to form oppositely reciprocated groups, each of said sections having a pair of spaced side walls provided on their upper edges with open sided transverse-slat-connected triangular members having a rearward inclination.

3. In a separating machine, a straw deck having longitudinally extending spaced 110 side walls and open sided triangular members on the upper edges of each side wall corresponding with those on the other, lateral slats connecting the points of the members on one side wall with the points of the 115 corresponding members on the other side wall, slats similarly connecting the bases of the members and connecting slats intermediate the slats mentioned.

In testimony whereof, I affix my signature in the presence of two witnesses.

PETER STORZUK.
